(57) **CLAIM**

The ornamental design for an electrostatic chuck, as shown and described.

DESCRIPTION

FIG. 1 is a front view of an electrostatic chuck illustrating my new design;

FIG. 2 is a rear view thereof;

FIG. 3 is a left side view thereof;

FIG. 4 is a right side view thereof;

FIG. 5 is a top plan view thereof, the bottom plan view being a mirror image of the plan view shown; and,

FIG. 6 is a partial cross-sectional view taken through line 6—6 of FIG. 1.

The broken lines shown in the figures are for illustrative purposes only and form no part of the claimed design.
